UNITED STATES PATENT OFFICE.

DANIEL CONBOY, OF TORONTO, CANADA.

DESIGN FOR A PLATE FOR BUGGY-TOPS.

SPECIFICATION forming part of Design No. 29,419, dated September 27, 1898.

Application filed February 17, 1898. Serial No. 670,714. Term of patent 7 years.

To all whom it may concern:

Be it known that I, DANIEL CONBOY, a citizen of the United States of America, residing at the city of Toronto, in the county of York

5 and Province of Ontario, Canada, have invented and produced a new and original Design for an Ornamental Plate for Buggy-Tops, &c., of which the following is a specification, reference being had to the accompanying drawing, forming part thereof.

The drawing represents a perspective view of my ornamental plate.

The essential feature of this design consists of a plate of the ornamental tongue shape shown in the drawing accompanying this application.

What I claim as new is—

The design for an ornamental plate, substantially as herein shown and described.

Toronto, February 12, 1898.

DANIEL CONBOY.
